UNITED STATES PATENT OFFICE.

PER GEORG HALVAR HALLONGREN, OF STOCKHOLM, SWEDEN.

DRIVING APPARATUS FOR BOATS.

1,118,930.

Specification of Letters Patent.

Patented Dec. 1, 1914.

Application filed September 8, 1914. Serial No. 860,767.

To all whom it may concern:

Be it known that I, PER GEORG HALVAR HALLONGREN, a subject of the King of Sweden, and resident of 11 Drottninggatan, 5 Stockholm, in the Kingdom of Sweden, architect, have invented certain new and useful Improvements in Driving Apparatuses for Boats, of which the following is a specification, reference being made to the accompanying drawing.

The present invention relates to that kind of driving apparatuses for boats (especially to so-called outboard-motors) the propeller shaft of which can be swung half a revolution in a horizontal plane, so that the boat carrying the driving apparatus can be driven forward as well as backward without reversal of the working direction of the motor belonging to the driving apparatus.

According to this invention the reversal of the direction of motion of the boat takes place by means of the tiller belonging to the driving apparatus being turnable also in vertical direction and connected with the propeller shaft in such a way that when the tiller is turned, that is to say is raised or lowered, from a position, corresponding to motion forward, into another position, the propeller shaft swings half a revolution, in consequence whereof the boat will be driven backward. Through a smaller turning of the tiller, it being raised or lowered, the boat can also by means of this arrangement be steered sideways.

On the accompanying drawing is shown by way of example a form of this invention, applied to an outboard motor.

Figure 1 shows the outboard motor seen from one side, while Figs. 2 and 3 show 40 horizontal sections of the same, taken along the lines A—A and B—B in Fig. 1.

The motor shaft and the extension of the same are—as is usual—surrounded by a sleeve 1 (the shaft sleeve) which is rotatable around said shaft and which sleeve at its lower end carries a casing 2, in which the propeller shaft is journaled. The rudder 3 is attached to a sleeve or ring 4 which can be turned around the shaft sleeve 1 and which ring by means of a bar 5, extending along the shaft sleeve, is connected with another sleeve or ring 6 which is likewise rotatable around the shaft sleeve 1 and to which the tiller 7 is fixed. When the tiller 55 7 is turned in the one or the other quarter in the transverse direction of the boat, the

boat will, as will easily be understood, be steered in accordance therewith. The tiller is fixed to the ring 6 by means of pivots 8, which extend from the ring in the transverse direction of the boat (in the ordinary position of the parts) and around these pivots the tiller can be turned in a vertical direction. An extension of the tiller 7, which extension is directed backward, is 60 provided with a conical toothed segment 9 which is in engagement with a conical toothed wheel 10, fixed to the shaft sleeve 1. When the tiller 7 is raised from the position, shown by full lines in Fig. 1, which 65 position corresponds to motion forward of the boat, into the position, shown by dotted lines in the same figure, the shaft sleeve 1 and thus also the propeller shaft is turned half a revolution, so that the boat will be 70 driven backward. When the tiller is thereafter lowered to the first-mentioned position, the propeller shaft is turned back into the position for forward motion. This 75 turning back of the propeller shaft takes place in a direction opposite to that of the first mentioned turning, which circumstance is of great importance, when the motor is being cooled by means of water, fed to the same from a pump, which revolves with the 80 propeller shaft and which pump is directly connected with the motor through a hose, as this hose in consequence thereof does not 85 become wound around the shaft sleeve.

It is evident that the arrangement described may also be used for steering the boat by raising or lowering the tiller from its position for motion forward. In this case the toothed segment 9 ought to be somewhat extended (to the right in Fig. 1) so 90 as to enable the propeller shaft to be turned in both directions from the position just mentioned.

The invention may be carried out otherwise than as stated by way of example. 100 Thus, for instance, the gearing between the tiller and the propeller shaft (or the shaft sleeve) may be of another type (it may consist of a straight rack connected with the tiller in a suitable manner and of a cylindrical toothed wheel), though the arrangement described is probably the simplest one.

Having now described my invention, what I claim as new and desire to secure by Letters Patent is:

1. Boat driving apparatus, comprising a propeller shaft having a propeller thereon,

means for supporting said shaft so that it can be swung in a horizontal plane, a steering tiller movable in a vertical plane, and connecting means between said tiller and propeller shaft, whereby the latter is swung when the former is moved in a vertical plane.

2. Boat driving apparatus, comprising a propeller shaft having a propeller thereon, 10 means for supporting said shaft so that it can be swung in a horizontal plane, a steering tiller movable in a vertical plane, a toothed segment connected to said tiller, a toothed wheel meshing with said segment, 15 and a connection between the propeller shaft and the toothed wheel, whereby the former is swung when the latter is rotated by the vertical movement of the tiller.

3. Boat driving apparatus, comprising a

propeller shaft having a propeller thereon, 20 a casing in which said shaft is mounted, means for supporting said casing so that it can be moved to swing the propeller shaft in a horizontal plane, a steering tiller movable in a vertical plane, a toothed segment 25 connected to said tiller, a toothed wheel meshing with said segment, and a sleeve connecting said wheel with said casing, so that the latter is swung when the former is rotated by the vertical movement of the 30 tiller.

In witness whereof I have hereunto set my hand in presence of two witnesses.

PER GEORG HALVAR HALLONGREN.
